SPRING STRUCTURE

Angelo Pittoni, Lynbrook, N. Y., assignor, by
mesne assignments, to Burton-Dixie Corpora-
tion, a corporation of Delaware

Application June 1, 1934, Serial No. 728,546

3 Claims. (Cl. 5—271)

This invention relates to spring structures such, for example, as bed springs, inner springs for mattresses, cushions or the like, and to the individual units employed in fabricating spring structures.

An ideal spring structure of the type set forth would be one having an infinite number of infinitely small springs so as to provide a yielding and flexible support at every point of the structure's surface. An object of this invention is to provide a spring structure constructed and arranged to produce a larger area of yieldable supporting surface per coil spring unit than has heretofore been possible.

15 A further object is to provide an improved construction of coil spring unit for use in manufacturing complete spring structures.

A still further object is to provide a spring structure of the type set forth which will be substantially noiseless in use.

These and other objects which will be apparent to those skilled in this art are accomplished by the invention illustrated in the accompanying drawings in which,

25 Fig. 1 is a top plan view of a spring structure embodying one form of the present invention;

Fig. 2 is a perspective view of one of the spring units employed in the structure shown in Fig. 1; and

30 Fig. 3 is a perspective view of a portion of inner spring construction incorporating a further feature of the present invention.

In carrying out the present invention, I employ a plurality of single spring units all of which are identical in shape, and the weight supporting surface of the spring structure is entirely formed by directly connecting together the end coils of these individual single spring units to form a spring structure of any desired size and type.

40 A preferred form of individual spring unit is illustrated in Fig. 2 and comprises a helical body portion 5 having a somewhat spiral end coil 6 of enlarged diameter connected to the body portion by helical convolutions 7 of relatively slight pitch.

45 The arrangement is such that the end coil cooperates with the helical convolution 7 when the unit is somewhat compressed, to provide a relatively large supporting area for the usual batt or other covering. The end coil 6 is formed with two U-shaped offsets 8 disposed 90° apart and two hinge-forming connecting loops 9 also disposed 90° apart and diametrically opposite to the U-shaped offsets 8. Instead of knotting the end of the wire to the coil 6, it is left free and so positioned relatively to the unit as to increase the

supporting area of the structure formed when the single units are connected together. Preferably the wire is shaped to form an extended arm 10 having an eye 11 in the end thereof.

In Fig. 2 the spring unit is shown as having the opposite ends formed alike, as is the case when the units are employed to form resilient fillers such as inner springs for mattresses, but it will be apparent that the invention is equally adapted to any type of coil springs such, for example, as those used in bed springs or the like. However, for the purposes of description and illustration, the invention will be considered as applied to an inner spring construction.

In forming such a structure, a plurality of single spring units are arranged in rows extending longitudinally and transversely of the structure, and the end coils thereof are connected directly together by crimping or bending the connecting loops 9 of each unit around the loop receiving offsets 8 of the adjacent units in the manner illustrated in Fig. 1. The end coil 6 of each unit is thus hinged directly to the end coil of each of the surrounding units and the projecting arm and eye 10 of the end coil projects into the space framed by surrounding units as shown most clearly in Fig. 1. In the case of an inner spring construction the end coils at each end of the units are connected in the manner described.

The result is an articulated spring structure having a surface of great flexibility and of large supporting area per unit spring. Hinging the end coils of the units directly together permits pivotal movement between adjacent units about axes extending at right angles to each other, both longitudinally and transversely of the finished structure. It will, of course, be apparent that the same flexibility can be obtained by using types of hinged connections between the individual units other than the particular form described and illustrated.

The combination of features including the enlarged diameter of the individual end coils 6, the slight pitch of the adjacent helical convolutions 7 connecting the end coils to the body portions 5, and the projecting arms 10 and eyes 11 result in a relatively large area of supporting surface per spring unit and produce a supporting surface having a relatively fine mesh without requiring a large number of spring units. As a result, the structure provides a sufficient supporting surface even with relatively wide center distances between the individual spring units.

In Fig. 3 there is shown a spring structure employing the individual units of the present inven-

tion and having silencers 12 in the form of strips of cotton felting extending longitudinally between the rows of spring units for the purpose of preventing contact between the coils of the separate units when they are subjected to distortion as a result of supporting a weight. The silencers are positioned between and in contact with the body portions 5 of the units so as to prevent the coils thereof from crunching together and producing an undesirable noise. At the same time, the silencers have some stiffening effect upon the coils 5 by cushioning the spring action and limiting the compression of the associated spring structure. The silencers are adapted for use with spring structures of any type or form.

It will be apparent that the distinguishing features of the present invention can be variously modified and adapted within the scope of the appended claims.

20 I claim:

1. The combination in a spring structure of a plurality of individual helical spring units arranged in transversely and longitudinally extending rows, the end coil of each unit being of greater diameter than the main body portion and connected to said body portion by a convolution of relatively slight pitch, the end coil of each unit being hinged to the end coils of adjacent units by having the wire of one coil wrapped around the

wire of an adjacent coil, and the ends of the spring wires being unknotted and extended into substantially the centers of the spaces framed by said units.

2. An articulated spring structure having a flexible resilient surface formed by the end coils of a plurality of individual helical springs arranged in rows extending longitudinally and transversely of the structure, the end coils of each spring being hinged to the end coils of adjacent springs by having the wire of one coil bent around the wire of another coil, the ends of the wires forming the end coils being unknotted and extended into substantially the centers of the spaces framed by said coils. 5

3. An articulated spring structure formed by a plurality of identical single spring units arranged in transversely and longitudinally extending rows, each unit comprising a helical body portion, an end coil of enlarged diameter connected to said body portion by a convolution of lesser diameter and relatively slight pitch, the end coils of adjacent units being directly hinged together by having the wire of one end coil wrapped around the wire of an adjacent end coil and the ends of the 10 wires forming said end coils projecting into substantially the centers of the spaces framed by said end coils. 10

15 ANGELO PITTONI.
